UNITED STATES PATENT OFFICE

DE WITT FOX, OF NEW YORK, N. Y.

DEMONSTRATING DISPLAY STAND FOR ELASTIC BELTS

Application filed June 11, 1928. Serial No. 284,460.

This invention relates to means for displaying such articles as belts, garters and the like, and at the same time providing for their ready demonstration, particularly in connection with such articles as are intentionally resilient. An object of the invention is to provide such an apparatus which shall be inexpensive, pleasing of appearance, and efficient in carrying out the purpose of mounting such articles for display upon a store counter or the like. An object of the invention also is to provide such an apparatus as will cooperate functionally to harness mechanical principles in combination with a belt or similar article for the general purpose as set forth.

The invention is pointed out more technically in the following claim, which is directed to illustrative embodiments described in the following specification and shown in the accompanying drawings solely for purposes of illustration and not limitation.

In the drawings, Fig. 1 is a perspective view of apparatus embodying the invention, and showing its combination in dash lines with an article being supported and demonstrated; Fig. 2 is a plan view of the apparatus; and Fig. 3 is a perspective view drawn to a reduced scale showing a modification.

A supporting pedestal A comprises a suitably extensive preferably disc-shaped base 1, and an upstanding central post 2. Upon the pedestal may be mounted an advertising plate 3.

A resistor B is supported by the post 2 preferably centrally of its length, and may conveniently comprise a bow or bar thrust 40 through and glued in a suitable perforation 3. Horizontally spaced distenders C are preferably formed as turned bosses to provide outwardly facing surfaces 4 and 5, the bosses being mounted in any suitable manner preferably fixedly to the ends of the resistor B, as by thrusting the ends of the resistor into suitably formed radial perforations 6 and 7 where they may be glued. The outwardly facing parts of surfaces of these bosses 4 and 5, adapted to engage and hold the belt, may

be of any suitable configuration, but are preferably arranged vertically. Objectively these surfaces should cause the belt to spread into gently curved bends, and it is preferable that these surfaces be cylindrical. The 55 geometrical elements of the cylindrical surfaces 4 and 5 are preferably substantially vertical. In connection with this description, although the surfaces 4 and 5 are a part of a right cylinder of revolution it is not 60 intended by the use of the term "cylindrical surface" to limit the construction to a surface of revolution, but the term "cylindrical surface" includes any surface generated by a line moving parallel to itself and following a curve. As the object of the surfaces 4 and 5 is to hold the belt in proper position 65 without causing sharp bends in it, it is considered within the scope of the invention, if the surfaces 4 and 5 are not actually 70 curved, to present such a contour as will not cause a sharp bend in the belt which forcibly engages these surfaces. The distenders C are preferably of substantial extent or width crosswise of their separation, 75 that is, crosswise of the resistor B, so that when opposite spans 8 and 9 of a belt D are looped about the distender C to be curved at its ends into curved portions 10 and 11 that the spans 8 and 9 will have substantial 80 separation and so that ready engagement by a finger 12 may be had with the interior face 14 of span 8 or the interior face 15 of span 9, readily to demonstrate its 85 stretchability and so also as to give a substantially unobstructed free display of these interior faces of the belt as well as of its exterior faces.

Functionally the belt D looped about the faces of the distenders 10 and 11 exerts a 90 forcible inward thrust or stress upon these distenders which is resisted by the resistor B which in turn supports the distenders together with the weight of the belt against gravity. In addition to the provisions of 95 the outwardly facing surfaces for shaping the ends of the belt loop into gentle curves of a radius greater than that which can cause injury to the belt, it is preferred that positive means be provided for fixing the hori- 100

zontal positioning of the belt and to prevent its slipping downwardly off the distenders C in the embodiments illustrated. This is provided by turning integrally with the distenders C an outstanding lower flange 16 for one distender and 17 for the other. It, however, is of course to be understood that this additional provision for engaging the lower edge 19 of the belt is by no means of necessity limited to a construction integral with the distenders.

In the modification of Fig. 3 the distenders C are not supported by the resistor B, but are formed as the upper part of a wood turning, the bottom of which comprises a pedestal A', the upper portion of which pedestal provides the flanges 16 and 17. The resistor B is also shown mounted in sockets 20 and 21 provided in the upper portion of the pedestal A'.

What I claim and desire to secure by United States Letters Patent is:—

A demonstrating display stand for belts and the like, comprising two horizontally spaced distenders, having outwardly positioned and outwardly facing surfaces free from sharp edges capable of imparting a sharp angular bend to the belt and adapted to engage and curve a belt disposed in two substantially parallel spans and at their ends looped about said distenders with a radius of curvature for the loops about said distenders greater than two times the thickness of said belt, said distenders being of substantial thickness in a direction crosswise to their separation to maintain a substantial separation between said opposite spans of said belt, and said surfaces being arranged substantially vertically; said distenders having outstanding retaining flanges at the bottom edge of said belt to prevent the gravity displacement of said belt, a resistor mounted to maintain the separation between said distenders and adapted to resist the inward stress of said belt upon said distenders and itself leaving space between said spans of said belt, whereby said spans of said belt are free for finger manipulations and inspection; and pedestal means for supporting said distenders and said resistor upon a horizontal surface.
